HIGHWAY MARKER

Henry G. Meigs, West Allis, Wis.

Application September 6, 1938, Serial No. 228,578

7 Claims. (Cl. 40—125)

This invention relates to improvements in highway markers. The present application is a continuation in part of my application No. 45,450 filed October 17, 1935, now Patent 2,151,277.

5 It is the primary object of the present invention to provide an effective reflecting sign which may be made from sheet metal having a reflecting surface in the form of a symbol and so arranged as to yield throughout an appropriate angle of view a reflection of approximately uniform brilliance rendering the symbolic form clearly apparent without glare.

In hundreds of experiments I have demonstrated that the shape and proportions of a reflecting symbol satisfactory in the foregoing particulars are extremely critical. Such symbols are ordinarily placed beside a highway, at varying distances from the center of the road. They may be located on a curve or on a straight section 20 of the road. They may be located on a level stretch of road or on either side of a hill. To serve their purpose they must be visible at a substantial distance and they must remain visible until the approaching vehicle gets very close to 25 the sign. Yet the distant vision cannot be achieved in such a way that the symbol will have its outlines obscured by glare when the observer is close. All of this must ordinarily be achieved in a manner such that the symbol will function 30 by light reflected solely from the headlamps of the vehicle in which the observer is riding.

I have found that the only way in which all objectives of a highway marker can successfully be achieved involves a structure in which the 35 entire surface of the symbol is substantially uniformly treated to provide beads or craters of well defined depth and spacing and curvature. It is important to the desired result that instead of being arranged in rows at right angles to each 40 other, the craters should be arranged in rows which intersect at an angle of 60 degrees, whereby the craters have a hexagonal pattern, each single crater (except at the borders of the symbol) being surrounded by six other craters. It is 45 also important to note that the surface of the symbol between the craters is not planiform but is slightly convex. These convex surfaces constitute the principal source of light for distant vision. The convex pattern produced by the 50 hexagonal arrangement of beads or craters is peculiarly suited to yield a clear and brilliant distant view of the symbol without glare. As the observer approaches the symbol and his angularity with respect to its surface becomes 55 more acute, due to its position beside the road,

the reflection from the convex surfaces of the symbol becomes less brilliant and the reflection from the concave surfaces of the symbol becomes more brilliant in substantially the same degree whereby the brilliance of the symbol remains substantially constant and free of glare at all points. 5

A preferred mounting for the symbol and other objectives of the present disclosure will be made apparent hereinafter.

In the drawings:

Fig. 1 is a front elevation of a symbol having a portion of its surface completed to illustrate a type of reflecting surface embodying this invention. 10

Fig. 2 is a greatly enlarged detail view in front elevation showing a portion of the reflecting surface of such a symbol as that illustrated in Fig. 1. 15

Fig. 3 is a greatly enlarged cross section taken on line 3—3 of Fig. 2. 20

Fig. 4 is a similarly enlarged detail view in cross section taken on line 4—4 of Fig. 2.

Fig. 5 is a front elevation of a mounted symbol on its target plate and post.

Fig. 6 is a detail view taken in section on line 6—6 of Fig. 5. 25

Fig. 7 is a detail view taken in section on line 7—7 of Fig. 5.

Fig. 8 is a view similar to Fig. 7 showing a modified type of supporting post to which the 30 same mounting arrangement is applied.

Fig. 9 is a view similar to Fig. 6 showing a modified type of symbol backing.

Fig. 10 is a diagrammatic plan view of a highway showing a preferred relation of the mounted 35 symbol thereto.

Like parts are identified by the same reference characters throughout the several views.

I shall first describe the improved reflecting surface which I have devised in order to produce 40 a brilliant and sharply outlined symbol which will maintain its brilliance throughout the range of view for which it is adapted and will not glare at any distance.

The reflecting surface shown at 15 in Fig. 1 45 preferably has the outline of the desired symbol, in this case a curved arrow. It may be cast, stamped or formed in any desired manner to provide a very specific type of configuration which I have found to be very important in the production of the desired result.

In order to provide the desired surface I prefer to stamp a thin sheet 16 of material between two dies, or one die and a matrix of rubber or the like, to produce therein a series of pits or craters 50

17 which have a highly critical ratio of depth to spacing and diameter. In the sizes in which highway symbols are ordinarily made, and for most other purposes, I have found that the diameter 5 may range from $\frac{1}{2}$ " to $\frac{3}{2}$ ", the preferred diameter being $\frac{1}{2}$ ". The depth of each crater from the original plane of the sheet in which it is formed is preferably .014", but its overall depth, due to the convex forming of the sheet 10 intermediate the craters, is preferably .018". The bottom area 18 of each crater is preferably concave on a $2\frac{1}{2}$ " radius over an area of .067" radius, and the side portions at 19 are concave on a radius of $\frac{1}{8}$ ", gradually merging into the 15 intervening convex surface 20 which is made on a radius of .187". These preferred dimensions and radii are indicated on the drawing in Fig. 4.

In Fig. 3 I have shown at the left the relative position of the sheet 16 prior to the forming of 20 the concave and convex surfaces therefrom. It will be noted from the foregoing that the bottom 18 of the crater 17 is preferably .014" below the surface of the original sheet, and the top of the intervening convex surface 20 is .004" 25 above the level of the original sheet. The total width of each crater 17 is preferably $\frac{1}{32}$ " and the space between centers of adjacent craters on the shortest possible dimension is preferably .686"

It is particularly to be noted that the pits 30 or craters 17 are set in rows on lines which are preferably not at right angles to each other but are drawn at about 60 degrees, as clearly shown both in Figs. 1 and 2. As a result of this arrangement any pit taken as a center will be found to 35 have six pits or craters surrounding it, and a line drawn to connect the centers of the surrounding pits or craters would be hexagon.

In actual practice I have used 22 gauge brass, marginally engaged about the edge flanges, of 40 a shoe 18 in accordance with the disclosure of my Patent No. 2,076,907 entitled "Highway markers," and after the die operation forming the pit or craters approximately .016" deep and $\frac{1}{32}$ " in diameter, I have chromium plated the reflecting surface 15. Chromium plating is well adapted to withstand the weather, but I may also use other plated or naturally reflecting surfaces such, for example, as the aluminum alloys known as "Alzak" and "Alcolite."

50 While the dimensions herein furnished may be somewhat changed and still give good results, I have found it undesirable to make any substantial change even in dimension. Moreover, where dimensions are changed the proportions herein disclosed should be maintained substantially constant. Even the buffing of a chromium plated surface may, if carelessly done, alter the characteristics of the symbol to such an extent that the flattening of the normally convex surfaces at 55 20 will increase the brilliance of the sign within a narrow angle of reflection but will decrease the angle through which the sign will have the desired degree of brilliance, thus decreasing its effective angle of use.

60 I have found that at substantial distances from a highway marker made in accordance with this invention, the largest proportion of the reflecting effect is produced by the areas 20. Due to the slight convexity of such areas the reflection is 65 maintained brilliant as the observer approaches the sign, until finally the reflection observed is almost solely attributable to the concave pits or craters. If the proportions above indicated are followed there will be no intervening point at 70 75 which reflection will be sharply reduced.

While the design of the reflecting surface herein disclosed is such as to produce a continuously brilliant effect as the observer approaches the symbol, and while the angle through which this brilliant reflection is observable is a substantial angle, nevertheless the best results require that the symbol should bear a predetermined relation to the highway. In Fig. 10 the highway is indicated at 22 and a target plate 23 bearing my improved reflecting symbol is so disposed 10 beside the highway as to deviate by approximately 2 degrees from a line at right angles to the highway. With the general plane of the reflecting surface at approximately 88 degrees to the center line of the highway, a maximum useful range of 15 brilliant view of the symbol will be provided approximately between the points A and B upon the highway.

The target plate 23 is conventionally provided with a reinforcing bead at 24 just within its 20 margin. I prefer that a similar bead should be used at 25 to outline the space to be occupied by the symbol 14, thus providing a shallow recess or pocket within the bead into which the symbol fits. I fold inwardly upon themselves at 25 26 the margins of the sheet 16 constituting the symbol, and secure the symbol to the target plate 23 by rivets 27, thus eliminating the shoe 28 which is shown in Fig. 9 and is sometimes used to reinforce the symbol 14.

In order that the target and symbol may be adjusted to the preferred angle shown in Fig. 10 upon a post previously set, I prefer the improved mounting parts shown in Figs. 5, 7 and 8. Each target plate 23 is preferably formed to provide 35 integrally a cylindrical channel of rectangular outline in elevation, the arcuate curve of the back of the channel extending transversely of the post as indicated at 30 in Fig. 7 and Fig. 8. There is such a channel at the bottom as well as the 40 top of the target. The arcuately curved surface of the channel is transversely slotted at 31 to receive a lag screw or bolt 32 or 33.

Behind the channel is a block 34 having a concave surface complementary to the channel and 45 provided preferably with lugs at 35 which, in case a wooden post 36 is used, will be pressed into the wood, and in the event that a metal channel post 37 is used, will embrace the outside of the post to prevent the block from turning. The 50 block is centrally apertured to receive the securing bolt or screw.

Within the channel is a block 38 in the form of a cylindrical sector complementary to the inner 55 concave surface of the channel 30. This block likewise has an aperture for the bolt or screw. Between the blocks 34 and 38 the target plate 23 may be shifted as to angle throughout the substantial range of adjustment permitted by the transverse slot 31 therein.

In the section illustrated in Fig. 3 the convexity of the high spot 20 of the symbol is very slight due to the extent to which the high spot 20 is elongated in this section. Yet even in this section the high spot is preferably slightly convex. Planiform or even rectilinear surfaces are to be avoided for the purposes of the present invention. Though the required convexity deviates but slightly from a plane, it is important in that it contributes the major portion of the light and assures that uniformity of reflection which makes the symbol appear to have uniformly distributed and equally brilliant illumination within its entire outline.

In accordance with the disclosure of my Pat- 75

ent No. 2,076,907, the symbol is preferably provided with a non-reflecting darkened border at 40, but it will be understood that this is not essential. The reflecting surfaces which are almost 5 planiform but slightly convex, should not be substantially in excess of 25% of the total convex area between the craters.

I claim:

1. A reflector comprising a member having a reflecting surface provided at substantially regularly spaced intervals with concave, shallow, circular pits in substantially hexagonal patterns, said reflecting surface having a sinuous portion substantially continuous and slightly rounded 10 convexly between said pits and merging with the concave surfaces thereof.
2. A reflector comprising a member having a reflecting surface provided with concave craters of diameters of the approximate order of $\frac{3}{2}''$ to 20 $\frac{5}{8}''$ and depths of the approximate order of .014" to .018", said craters being arranged in substantially hexagonal patterns at substantially regular spacings of the general order of .686" in rows intersecting at 60 degrees, the said surface having 25 a continuous and only slightly convex portion between said craters.
3. A reflector comprising a member having a reflecting surface whereof at least seventy-five percent of the area comprises circular craters 30 regularly spaced in rows intersecting at sixty degrees to form hexagonal patterns, the remaining surface being continuous and slightly convex between said craters, each such crater comprising a shallow concavity ranging in diameter approximately 35 between $\frac{3}{2}''$ and $\frac{5}{8}''$ and approximating .018" in depth with its bottom reflecting surface relatively slightly concave on approximately a $2\frac{1}{2}''$ radius and its side more sharply concave on approximatley $\frac{1}{8}''$ radius gradually merging with 40 an annular surface convex on approximately .187 radius merging in turn with the slightly convex surface intervening between said craters.
4. A reflector comprising a member having a reflecting surface including at spaced intervals a multiplicity of shallow, concave and substantially circular pits, said surface having portions of substantial area extending continuously and sinuously between said pits and slightly rounded convexly toward and merging gradually with the concave surfaces of the respective pits. 45
5. In a device of the character described, a

reflector having a reflecting portion of its surface formed in the outline of a symbol and provided throughout said portion with substantially circular craters arranged in uniformly spaced relation in hexagonal patterns on lines intersecting at approximately 60 degrees, said craters comprising shallow concave depressions and said reflector having between the respective craters sinuous intervening areas slightly convex and continuous about the respective craters, each of 10 said craters having a diameter between $\frac{3}{2}''$ and $\frac{5}{8}''$ and a total depth from said convex areas of the approximate order of .018".

6. A light reflecting sign of sheet material comprising a single ply blank of relatively rigid and 15 durable sheet metal provided with a continuity of circular offset surface elements of very shallow concavely curved contour closely arranged in spaced relationship with only narrow sinuous and very slightly convex surface areas extending continuously between said offset concave surface elements, said sheet material having a light reflecting surface on the entire face toward which said offset elements are concave and on which said sinuous areas are disposed, said areas constituting 20 means for distant reflection and said elements reinforcing the sheet and constituting individual reflectors sensitive to illumination over a wide range of angles.

7. A reflecting symbol of the class described, 30 comprising a reflector having a definitely demarcated outline in the predetermined form of a significant symbol and provided within said outline with a reflecting surface formed to provide shallow pits or depressions and an intervening 35 sinuous slightly convex area continuous about said pits and almost flat to provide for distant reflection, said pits or depressions being spaced substantially uniformly from each other in a definite and approximately hexagonal pattern and being 40 generally circular in form with their bottoms only slightly concave and their sides convexly merging into said sinuous intervening areas, the size and arrangement of the pits being such that in no direction on said surface does said sinuous 45 area extend rectilinearly between said pits, whereby the significant form and outline of the reflector is brilliantly apparent without glare at a wide range of angles respecting the path of light thereto.

HENRY G. MEIGS. 50

CERTIFICATE OF CORRECTION.

Patent No. 2,217,125.

October 8, 1940.

HENRY G. MEIGS.

It is hereby certified that error appears in the printed specification of the above numbered patent requiring correction as follows: Page 2, first column, line 10, for "0.18," read --.018:--; and that the said Letters Patent should be read with this correction therein that the same may conform to the record of the case in the Patent Office.

Signed and sealed this 12th day of November, A. D. 1940.
